(57) CLAIM

The ornamental design for an ornamental hanger plate, as shown and described.

DESCRIPTION

FIG. 1 is a perspective view of an ornamental hanger plate, showing my new design,

FIG. 2 is a front side elevational view thereof;

FIG. 3 is a right side elevational view thereof;

FIG. 4 is a top side plan view thereof;

FIG. 5 is a bottom side plan view thereof;

FIG. 6 is a back side elevational view thereof; and,

FIG. 7 is a reduced scale view showing my new design in association with a perspective view of a door opening to living quarters, the broken line depiction thereof is for illustrative purposes only and forms no part of the claimed invention.
